UNITED STATES PATENT OFFICE.

EMIL MARIUS ERIKSEN, OF OSLO, NORWAY.

SKI TIE.

Application filed September 4, 1925, Serial No. 54,574, and in Norway September 11, 1924.

The present invention relates to ski ties of the type which are provided with a rear strap, and in which the toe irons are relatively adjustable and also are provided with 5 inwardly projecting vertically adjustable pieces or tongues, so that the ski tie may be adjusted in accordance both with the width and the thickness of the shoe sole.

The drawing illustrates an embodiment of 10 the invention, in which—

Fig. 1 is a side view of the ski tie.

Fig. 2 is part of a top view thereof.

Fig. 3 shows a section on the line III—III in Fig. 1.

Fig. 4 is a front view of one tongue and the securing means therefor and

Fig. 5 shows a section on the line V—V in Fig. 2.

At the drawing 1 designates the ski and 2 the horizontal parts of the toe irons. In each of the said horizontal parts are provided a number of slots 3 the sides of which are inclined in such manner that the slots are narrower near the ski. In each slot is placed 25 a clamping piece 4 the sides of which are inclined so as to fit in the slot. The said pieces are somewhat shorter than the slots. Each clamping piece also has an opening which receives a screw 5 adapted to be screwed into 30 the ski. Thus the toe irons are secured to the ski by screwing in the screws 5 whereby the inclined sides of the clamping pieces press against the inclined sides of the slots and thereby firmly press the toe irons against the 35 ski. It will be understood that the clamping means here described brings the advantage that no part thereof project to any material extent above the surface of the toe iron parts 2, as will be seen in Fig. 5. To adjust the 40 position of the toe irons sidewardly it is only necessary to unscrew the screws 5 so much that the pressure of the clamping pieces 4 against the toe iron parts 2 is relieved when the toe irons may be displaced to the desired 45 extent and then secured in adjusted position only by again tightening the screws 5. Thus the adjustment is made without displacing the screws 5.

To secure a better gripping action between 50 the clamping pieces 4 and the irons 2, the inclined sides of the said pieces and of the slots 3 may be corrugated as indicated in Fig. 2.

The vertical part 9 of each toe iron is provided with a vertical slot 8 which receives a 55 plate piece 7 of dovetailed cross section slid-

ably mounted therein. The said plate piece is provided with an inwardly projecting tongue 6 under which the edge part of the shoe sole rests when the ski tie is in use, as indicated in Fig. 4. The plate piece 7 also carries a pin 10 projecting outwardly therefrom and carrying a head 11 at its free end. By placing a U-shaped wedge 12 between the head 11 and the vertical portion 9 of the toe iron, 60 the plate piece 7 may be secured in the desired height position. Preferably the said wedge 12 is formed on the end of an arm 13 pivotally arranged on a pivot 14 secured to the rear part of the toe iron. The said 65 pivot 14 also serves as an attachment pin for the rear strap, the ferrule of which is indicated at 15. The arm 13 will serve to stay the pivot 14 against the bending action exerted thereupon by the rear strap. 70

To provide for an easy removal of the rear strap and its ferrule 15, the ferrule is given the shape of a hook the outer opening 16 of which is narrow and corresponds with a reduced portion 17 on the pivot 14. Said 80 reduced portion 17 is so formed and placed on the pivot that the hook only may be removed after having been swung downward to a substantially vertical position.

Having now particularly described and 85 ascertained the nature of my said invention and in what manner the same is to be performed, I declare that what I claim is:

1. In a ski tie, toe irons including horizontal attaching portions and vertical supporting portions, inwardly projecting tongues vertically adjustable on the vertical portions, the horizontal portion of each iron being provided with slots the wall of which are inclined, and clamping irons mounted in the 90 slots for securing the attaching portions to the upper surface of the ski and having the side edges inclined so that the upper surface lies flush with the upper surface of the horizontal attaching portion, substantially 95 as and for the purposes set forth.

2. A ski tie in accordance with claim 1, in which the inclined edges of the slots and clamping irons are corrugated.

3. In a ski tie, toe irons including vertical 105 attaching portions provided with vertical slots, plate pieces vertically adjustable in said slots, and inwardly projecting tongues carried by the plate pieces, and wedges for securing the plate pieces in the desired position of vertical adjustment. 110

4. A ski tie in accordance with claim 3, in

which a pin is carried by each plate piece and projects through the slot, a head on the free end of the pin, and a U-shaped wedge piece arranged between the head and the vertical portion of the toe iron.

5 A ski tie in accordance with claim 3, in which a pin is carried by each plate piece and projects through the slot, a head on the free end of the pin, an arm pivotally secured to the rear part of the vertical supporting portion of the toe iron, and a U-

shaped wedge piece carried by the free end of the arm and adapted for engagement about the headed pin for clamping the plate in the desired position of adjustment.

6. A ski tie in accordance with claim 1, wherein the clamping pieces are provided with apertures, and screws arranged through the apertures for clamping the clamping irons and toe irons in position.

In testimony whereof I affix my signature.

EMIL MARIUS ERIKSEN.
